RING PROCESSING APPARATUS

Eugene L. Mackey, Fairview Park, Ohio, assignor to The Yoder Company, Cleveland, Ohio, a corporation of Ohio

Filed Mar. 29, 1960, Ser. No. 18,430

1 Claim. (Cl. 113—127)

This invention relates generally, as indicated, to a ring processing apparatus and more particularly to an apparatus for forming and finishing drop-center automobile wheel rims.

In modern automobiles, the innovation of the smaller wheel and the tubeless tire has necessitated a means accurately and quickly to form such drop-center wheel rims that will not only produce a rim capable of withstanding the high speed stresses and shocks of modern automotive travel but will also provide a perfectly uniform airtight inner wall and seal for such tubeless tires.

The apparatus of this invention constitutes generally means to close the ends of coiled stock usually in drop-center form and then to finish such rim by removing the bead and subsequently spinning and pressing in a final sizing operation to produce a uniform finished article. This process and apparatus is particularly adapted for use in conjunction with the machine for coiling and cutting off rings shown in the co-pending application of Ambro Todoran et al., entitled "Ring Coiling and Cut-Off Machine," Serial No. 745,869.

With the foregoing in mind, it is a primary object of this invention to provide a machine which will take coiled stock having closely spaced ends and which will accurately and economically close such stock into a homogeneous metal ring.

It is yet another important object of my invention to provide an apparatus which will economically and accurately produce small diameter drop-center wheel rims of a uniform curvature, diameter and quality.

It is yet a further object of my invention to provide a machine that will produce rings of uniform radius and curvature with a minimum loss due to waste material.

It is still another object of my invention to provide a machine for producing drop-center wheel rims and the like at a rapid rate with fewer pieces of apparatus occupying less floor space and using fewer man hours than are required by using present methods and apparatus known to me.

Other objects and advantages of the present invention will become apparent as the following description proceeds.

To the accomplishment of the foregoing and related ends, the invention, then, comprises the features herein-after fully described and particularly pointed out in the claim, the following description and the annexed drawings setting forth in detail certain illustrative embodiments of the invention, these being indicative, however, of but a few of the various ways in which the principles of the invention may be employed.

In said annexed drawings:

FIGS. 1 and 1A constitute a single schematic plan of mechanisms embodying the principles of my invention, illustrating the layout thereof;

FIGS. 2 and 2A comprise a single schematic elevational view of the apparatus shown in FIG. 1 with the cleaning station omitted;

FIG. 3 is an enlarged fragmentary front elevation of my ring orientation station taken along line 3—3 of FIG. 1;

FIG. 4 is a side elevation and section of the apparatus shown in FIG. 3 as viewed on line 4—4 thereof;

FIG. 5 is a fragmentary horizontal section taken substantially on the line 5—5 of FIG. 4;

2

FIG. 6 is a front elevation of my loading apparatus to assist the transfer of the ring from the orientation station to my index table taken on line 6—6 of FIG. 2 but shown in its receiving position;

5 FIG. 7 is a side elevational view of such loading apparatus taken substantially on line 7—7 of FIG. 1;

FIG. 8 is a fragmentary sectional view of an index table that may be employed with the illustrated embodiment of my invention taken on line 8—8 of FIG. 1;

10 FIG. 9 is a top plan view of such table with portions thereof removed for clarity of illustration;

FIG. 10 is a fragmentary sectional view of the operating mechanism for such index table taken on line 10—10 of FIG. 8;

15 FIG. 11 is a fragmentary sectional view of the locking pin mechanism employed with my index table taken on line 11—11 of FIG. 10;

FIG. 12 is a fragmentary front elevation of the clamping mechanisms employed firmly to clamp such ring to my illustrated index table;

FIG. 13 is a fragmentary sectional view of the clamping mechanism of FIG. 12 taken on line 13—13;

FIG. 14 is a fragmentary sectional elevation of the mechanism employed to unload the wheel rim from my index table taken on line 14—14 of FIG. 1;

FIG. 15 is a top plan view of the mechanism shown in FIG. 14;

FIG. 16 is a fragmentary sectional view taken substantially on the line 16—16 of FIG. 14;

FIG. 17 is a front elevation of the milling apparatus that may be employed with my invention taken on line 17—17 of FIG. 1;

FIG. 18 is a fragmentary sectional view of my milling apparatus as taken on line 18—18 of FIG. 17;

35 FIG. 19 is a schematic diagram of an electrical circuit that may be employed to control the orientation and load mechanisms of my apparatus;

FIG. 20 is a schematic diagram of an electrical circuit that may be employed to control my index mechanism;

40 FIG. 21 is a partial schematic diagram of an electrical circuit that may be employed to control my gap closing, table unloading and milling or finishing apparatus; and

45 FIGS. 22 through 26 are schematic diagrams of pneumatic and hydraulic controls that may be employed in conjunction with my electric circuits for actuating the various components of my mechanism.

50 Referring now to said annexed drawings and more particularly to FIGS. 1, 1A, 2 and 2A, there is shown the layout of the entire apparatus for economically and uniformly producing drop-center wheel rims from flat steel strip.

55 As seen first in FIG. 2A, the steel strip is supplied by a suitable coil reel 1 feeding strip to be formed to drop-center or channel shape and then coiled and cut off in the forming machine 2. This machine constitutes generally the subject matter of the aforementioned Todoran et al. application, Ser. No. 745,869 and, of course, is not necessarily a part of my invention. The stock is coiled in such forming machine to produce a planar circular cutoff ring in which the ends are closely spaced apart forming a slight gap in such ring. The problem then comprises closing such gap and then accurately finishing and sizing such rim so that it readily may be assembled with a spider to form the completed automobile wheel.

Briefly, the coiled stock is removed from the forming machine onto a power driven elevator conveyor 3 and deflected therefrom onto two oppositely extending inclined ramps 4 and 5 by an escapement pivoting type gate 6. In this manner, one ring at a time is deflected alternately onto each ramp 4 and 5.

The rings roll down the ramp 5 to an orientation station generally shown at 7. Here the rings are rotated to locate the gap therein in a predetermined position. Then, maintaining the gap in such predetermined position, the rings are transferred to a loading station generally shown at 8 to be presented to an index table shown at 9.

Here each ring is clamped firmly to the table with such gap in its proper oriented position and the ring is indexed clockwise successively through a cleaning station generally shown at 10, a gap closing and welding station generally shown at 11 and an unloading station generally shown at 12. The unloading station 12 comprises a means to transfer the work from the index table 9 to a bead milling apparatus shown at 13. Here, the area of the rim which constitutes the closed gap is accurately milled and the work is then transferred to a ramp 14 to be moved into position at aplanishing and sizing station shown at 15 wherein the work is finished to the proper size and curvature. From here, the rims are ejected as at 16 subsequently to be assembled with the wheel spider to form a complete automobile wheel.

The ramp 4 leads to apparatus which is identical in form to the apparatus shown by the reference numerals 7 through 16 inclusive. Such duplicative apparatus is desirable for the fast production of wheel rims since the capacity of the forming machine 2 is approximately twice the capacity of the ring processing apparatus generally illustrated by such reference numerals 7 through 16 inclusive. In this manner, an identical number of wheel rims will be ejected at point 17 as are ejected at 16 and the combined total will be the identical number of rings produced by the forming machine 2.

The escapement type gate 6 may be suitably actuated by a pneumatic cylinder controlled by a solenoid operated valve which is in turn controlled by a relay operated by limit switches on the conveyor 3. In this manner, one rim at a time will be removed from the conveyor 3 alternately onto the ramps 4 and 5.

The Orientation Station (FIGS. 3-5)

Referring now more particularly to FIG. 3, it will be seen that the coiled ring R rolls down the ramp 5 from the conveyor 3 to contact a control gate 20. At the proper moment, gate 20 will be removed from its path to permit the ring R to enter the orientation mechanism by dropping into a cradle 21 which includes two spaced ring supports 22 and 23. The ring supports are carried for vertical reciprocation on spaced supports 24 and 25. Two vertically extending guide bars 26 and 27 extend from the ring supports upwardly through such supports 24 and 25 and such cradle is actuated for vertical movement by an air cylinder 28, the rod of which is connected to the cradle 21 as shown at 29 and the cylinder of which is connected to support plate 30 secured between the supports 24 and 25. The plate 30 has a configuration more clearly shown in FIG. 5 and includes a lip 31 to enclose the edge of the ring R and act as a stop as the ring rolls into the cradle 21. The plate 30 also includes a beveled portion 32 terminating in a rearward extension to assist the proper nesting of the ring R thereagainst. The rearward extension, of course, will prevent a ring R inadvertently released by gate 20 from fouling the movement of the cradle hereinafter described.

After the ring is seated within the cradle 21, the piston 29 is actuated to raise the cradle to position the ring against two idler rolls 33 and 34. When the ring is in this raised position, the ring will contact orientation blade 35 resiliently compressing the fluid within cylinder 36 which acts as an air spring resiliently to hold the orientation blade 35 in its lowermost position. The movement of the orientation blade then actuates a cylinder 40 to swing a drive wheel 41 about pivot 42 to contact the ring R in its uppermost position. A motor 43 is energized by the movement of such roll 41 thereby to drive such roll in its position of engagement against the ring R thus to

rotate the same under a nominal torque until the blade 35 is pushed into the gap or slot between the juxtaposed ends of the ring by the compressed fluid within cylinder 36.

The ring R is now oriented in its proper predetermined position for presentation subsequently to the cleaning, gap closing and finishing operations.

When the cylinder 36 forces the blade 35 into the gap, and the cylinder 40 retracts the drive roll 41, a suitable limit switch, subsequently to be described, actuates cylinder 44 to move the cradle 21 holding the wheel in its oriented position to the next or loading station 8. The supports 24 and 25 are joined by a plate 45 as more clearly seen in FIG. 5 to which the rod 46 of the cylinder 44 is connected. Suitable guides 47 and 48 are employed to guide the ring holding apparatus to its extended position shown in phantom lines at 49 in FIG. 4. In this manner, the ring is nested in its proper oriented position supported on the raised cradle 21 against the plate 30 to be transferred to the loading apparatus shown in more detail in FIGS. 6 and 7.

Referring now to FIG. 6, it will be seen that the ring R, supported on members 22 and 23, is positioned above the loading mechanism 8. Simultaneously with the actuation of cylinder 44, load travel cylinder 50 actuates 25 to position the loading mechanism 8 from the position shown by phantom lines at 51 to the extended loading position. When cylinder 44 is in its proper extended position, cylinder 52 is actuated to raise yoke 53 to lift the ring R off supports 22 and 23 of the cradle 21. The 30 yoke 53 is mounted in slides 54 and 55 and has thereon two bearing rollers 56 and 57 to contact the ring R. The yoke 53 when extended actuates a suitable limit switch hereinafter described to retract cylinder 44 to position the orientation station in its proper original position to receive the next ring. The cylinder 40 having retracted after the blade 35 entered the slot, the cylinder 28 need only extend to lower the cradle 21 to the proper position to receive the next ring when the gate 20 is subsequently removed. The desired modus operandi will subsequently be more clearly delineated.

The loading station 8 is mounted on a slideway formed by two guides 58 and 59 and is moved therealong by cylinder 50. The loading station merely comprises a means to raise the ring in its proper oriented condition 45 against upper stationary clamping shoes so that it may be clamped on the index table 9 by actuation of lower clamping shoes.

Index Table and Clamp (FIGS. 8-13)

Referring now to FIG. 8, my index table 9 includes a non-rotatable base 60 including an upstanding column 61 in which is concentrically mounted a support column 62, supporting thereon a platform 63 for a purpose hereinafter described. The rotatable portion 64 of my table is journaled to the upstanding column 61 by means of suitable vertically spaced anti-friction bearings 65 and 66. These may preferably be tapered roller bearings firmly to absorb the thrusts on such table hereinafter described. The rotatable portion of my table is of a general square configuration as shown more clearly in FIG. 9 and has reinforced corner portions 67 joined by gussets 68 and reinforcing ribs 69. The table thus presents four open portions 70, 71, 72 and 73 at each side of which are secured plates 74 and 75 of the general configuration more clearly shown in FIG. 12. These plates may be secured to the table portion 64 in the relative positions shown in FIG. 12, each plate 74 and 75 having a cutout portion 76 and 77 respectively, through which are positioned my toggle operated clamping mechanisms generally shown at 78 in FIG. 13. The clamping mechanisms comprise in reality a pair of clamping mechanisms 79 and 80 essentially identical in form actuating respectively clamps 81 and 82. These clamps position and firmly hold the ring on the index table at the four

respective stations. The clamps include two substantially fixed upper clamps 83 and 84 firmly secured for slight relative movement to extensions 85 and 86 on the plates 74 and 75 respectively. The configuration of these clamps is more clearly shown in FIG. 13 and they each provide a pivot 87 for an angle member 88 supporting the lower clamp shoes 89. The angle member 88 comprises two spaced angle pivots or bell cranks 90 and 91 supporting plates 92 to which are secured lower clamping shoes 89. Secured, as by pins 93, through the plates 90 and 91, is a toggle link 94 pivotally connected to angle toggle links 95 pivoted interiorly of the plates 74 and 75 as at 96. Pivotally connecting the links 94 and 95 are suitable pivot pins 97 against which abuts my actuating mechanisms hereinafter described. It will now be seen that the ring R will be firmly clamped between the upper and lower shoes of each clamping mechanism with the gap in such ring centrally positioned between each such clamping mechanism as shown at 98. Each of the toggle mechanisms 79 and 80 are essentially identical in form and operate firmly to hold the ring at positions slightly spaced from yet juxtaposed to such oriented gap.

The toggle mechanisms are actuated by two stationary cylinders 100 and 101 identical in form which are mounted on platform 63 of the interior column 62. The piston of each cylinder includes a vertically extending actuating head 102 and 103 respectively, to contact member 94 at pivot 97 of the lower toggle arm 95 on linkage 78 and 79 to shove it from the phantom line unlocking position shown in FIG. 13 to the full line, in-line locking position shown. Suitable guides 104 and 105 are provided for each shoe to keep the piston of the cylinders 100 and 101 from rotating and thus moving the heads 102 and 103 out of the vertically aligned illustrated position. It can now be seen that each pair of toggle linkages 79 and 80 will be actuated to the locking position at one station only of my four station indexing mechanism.

Mounted on the platform 106 above the pair of cylinders 100 and 101 is a pivotally mounted gauging blade 107. This blade is mounted to swing about pivot 108 and is actuated by cylinder 109. This blade will be employed properly to position and maintain the juxtaposed ends of my coiled ring in the proper relative positions. Once the clamping mechanisms have been actuated, the blade, by actuation of the cylinder 109, will be removed for the subsequent cleaning and gap closing operations.

Now referring to FIGS. 8, 10 and 11, it will be seen that my table is rotated by a main actuating cylinder 110 having a rack 111 mounted on the rod end thereof to engage a ring gear 112 secured around the bottom end of the rotatable part of my table positioned adjacent the bearing 65. I also provide a locking cylinder 113 actuating a locking pin 114 insertable in openings 115 positioned about the table firmly to hold such table in its four respective stations accurately to present the work to the proper mechanisms. I also provide a latching cylinder 116, the rod 117 of which actuates spring loaded drive pawl 118 to clutch the ring gear to the table to rotate it therewith, the pawl 118 being mounted on such ring gear segment. Thus when the pawl is released, the gear 112 will rotate with respect to the table.

When the table is rotated in its clockwise direction as seen in FIG. 10 by retraction of cylinder 110, both cylinders 116 and 113 are retracted. The table then contacts a limit switch hereinafter described causing the cylinder 116 to extend unlatching the spring loaded drive pawl 118. This now permits the cylinder 110 to extend to move the unclutched gear and hence the drive pawl in its released position reversely through the 90° arc to snap into and be latched in the next preceding recess 119. When it is so latched as shown in FIG. 10 and after the completion of the work operation, the table

will again be moved through an arc of 90° by the retraction of cylinder 110. Cylinder 113 will extend at the same time as cylinder 116 firmly to lock the table in its proper position and, of course, will retract to unlock the table prior to the indexing thereof.

The Gap Cleaning Station (FIG. 1)

As shown schematically in FIG. 1, the first work station may be a gap cleaning station thoroughly to condition the gap for the subsequent closing operation. This station may take the form of a power driven abrasive wheel, milling blade or wire brush 120 to enter and clean the gap for the subsequent welding or closing operation. This brush is driven for rotation by motor 121 through transmission 122 and pivoted belt or chain drive 123 moved by cylinder 124. In this manner, the rotating cleaning tool may be lowered into the gap to condition it for the subsequent welding operation.

The Gap Closing Station (FIGS. 1 and 2)

The welding or gap closing station generally comprises an extensible platen 125 which extends to present a forging cylinder 126 and a backup 127 behind the opposite clamp structures 83 and 84. Pivotally mounted between the guides 128 and 129 for such welding platen 125 is a transformer 130 supplying R-F current to removably mounted welding shoes 131. These shoes snugly fit on each side of the gap in the ring in the space 98 between the clamps 83 and 84 thoroughly to heat the area of the gap to a welding temperature when current is applied. The welding platen is actuated by a cylinder 132 to move the forging cylinder into and out of forging position when the table has been properly indexed. My welding apparatus is described and claimed in more detail in my co-pending application entitled "Ring Welding Apparatus," Serial No. 18,360, filed simultaneously herewith.

The Table Unloading Mechanism (FIGS. 14, 15 and 16)

40 My unloading mechanism is mounted on a stand 135 positioned opposite the fourth or last work station of my index table 9. An upstanding column 136 is rigidly mounted on such stand and mounted on such column is a rotatable sleeve or tube 137. Platform 138 is constructed on such rotatable tube or sleeve and has mounted thereon cylinder 139 and four brackets 140 and enclosing guides 141 and 142. The rod 143 of the cylinder 139 is fastened to my unloading clamp arm 144. Laterally positioned on the unloading clamping arm 144 are two pneumatic cylinders 145 and 146 each actuating pivoted clamps 147 allochirally identical in form to grip the edge or bead of the ring with adjustable shoes 148 and 149 respectively.

55 When the ring R is positioned in such unloading station by the index table, the cylinder 139 is actuated to extend unload clamping arm 144 to a position wherein the clamping shoes 148 and 149 will grip a bead of such ring. As shown, when the unload clamping arm has firmly grasped the ring R, cylinder 150 mounted beneath the index table is actuated sliding upwardly member 151 to contact the middle pivot 97 of the toggle mechanisms 79 and 80 respectively to release the now closed ring from the respective clamping shoes.

60 Subsequently, cylinder 152 is retracted to lower the platform 138, the rod 153 of such cylinder being firmly secured to plate 154 which is in turn secured to slideable sleeve 137. Surrounding the sleeve 137 is a wide ring gear 155 engaging rack 160 actuated by cylinder 161. (Note FIG. 16.) As shown by the phantom line ring positions in FIG. 14, the cylinder 152 is actuated to lower the platform 138 to withdraw the ring from the toggle clamps, the cylinder 139 is retracted, and cylinder 161 is actuated to rotate the platform through an arc of 180°. The cylinder 139 is then extended to position the ring 75 properly at the next or work finishing station.

The Ring Milling Apparatus

The ring milling apparatus 13 includes a work support 165, the base of which houses a lift cylinder 166 having rod 167 attached to slide 168 secured between upstanding guides 169 and 170. Positioned on the top of the slide 168 are arcuate spaced rails 171 and 172. A rockable work support 173 is mounted on such rails by means of upper and lower wheels 174 and 175 respectively. In the illustrated embodiment, there are two wheels above and one below each of the rails 171 and 172. The rockable work support includes the pendently mounted cylinder 176 actuating pivot clamp 177.

It will now be seen that the work support 173 provides a work-engaging shoe 178 having pivoted shoe 179 of clamp 177 engaging the upper portion of the ring firmly to hold it on such work-engaging shoe 178.

The milling cutters comprise power driven rotary tools 180 and 181 of a conventional nature both of which are mounted on respective shafts or spindles 182 and 183. Both such shafts are driven through respective belt drives 184 and 185 from a suitable motor 186 through a transmission. The lower milling cutter 181 is mounted for vertical reciprocation on guides 187. The lower milling cutter is actuated for such vertical movement by cylinder 188, the rod 189 of which is attached to the lower milling cutter shaft housing as shown at 190. Both milling cutters are mounted on platform 191 for horizontal reciprocation, the platform 191 being connected to the rod 192 of cylinder 193. In this manner, the cutter 181 may be moved downwardly with respect to cutter 180 and both cutters may be traversed horizontally.

When the unloading station has positioned the ring R in its extended position shown in phantom lines in FIG. 14, the cylinder 166 can now be actuated to raise the lower clamping shoe 178 against the bottom of the ring. Cylinder 176 is then actuated to bring the shoe 179 of clamp 177 down firmly to clamp the ring on the rockable support 173. The clamping cylinders 145 and 146 are then released and the unloading station returns to grasp the next ring. At this time, the cylinder 188 has been retracted and the lower cutter 181 is in its lowermost position so that the unloading mechanism will position the ring R about such lower cutter. Cylinders 188 and 166 are actuated to close the position of the milling cutters and hold the ring R firmly in the proper position therebetween.

The cylinder 194 is then actuated, the rod 195 of which is connected to arm 196 fastened to the rockable mount 173 thereby to rock the mount and the ring clamped thereon through an arc sufficient for the cutters 180 and 181 effectively to remove the weld bead formed by the gap closing station. In this manner, the cylinder 176 will pivot within the slide 168 maintaining the clamping shoe 179 firmly against the inner portion of the ring R. I have found that a single actuation of the cylinder 194 is sufficient effectively to remove the weld bead. A suitable limit switch may deenergize the cylinder 194 at the end of its stroke to return the mount 173 to its original position. The cutters then move apart by actuation of the cylinder 188. The cylinder 166 lowers the wheel away from the upper cutter 180, and both cutters are retracted by cylinder 193. When this is done, a suitable kickout arm 197 actuated by air cylinder 198 removes the ring from the support 173 after the clamping shoe 179 has been pivoted out of the way.

Chip chutes 199 and 200 may be employed mounted for movement with the lower cutter effectively to clear the chips from the machine. Guide rollers 201 and 202 may also be provided to assist in the positioning of the ring against the top cutter 180.

The Planishing and Sizing Operation

The kickout device 197 kicks the ring onto ramp 14 to roll down to be positioned between interior sizing roll

203 and exterior sizing roll 204. The interior roll is formed from two laterally movable mating rolls whereby the wheel may be dropped therebetween and the rolls positioned completely to fill the interior portion thereof. 5 Exterior roll 204 is then forced against such rim and is rapidly rotated to complete the planishing and sizing of the ring. A final removal device will kick out the ring at point 16 for storage, shipment or the subsequent spider welding operation. The milling and finishing structures 10 herein described are illustrated and claimed per se in my co-pending application entitled "Ring Finishing Apparatus," Serial No. 18,359 filed even date herewith.

The Operation and Actuation Sequence of the Component Parts (FIGS. 19-26)

15 Referring now more particularly to FIGS. 3, 4, 5, 19 and 22, the operation of my mechanism will be seen to be as follows.

Orientation and Loading Stations

The rings formed by the machine 2 are transferred up the conveyor 3 to be removed therefrom by the escapement gate 6 to be discharged alternately on ramps 4 and 5. The ring discharged on ramp 5 rolls down and comes 20 to rest against solenoid operated ramp gate 20. When in contact with the gate, the ring is ready to be discharged onto the cradle by actuation of limit switch 210 which is closed when the cradle is in its lowermost receiving position. The operation sequence of my ring 25 processing mechanism is now ready to commence. The operator may actuate switch 211 to energize orientation motor 43, such motor closing switch 212 to complete a holding circuit around the switch 220 and switch 213 permitting the energization of my orientation and loading 30 station through mains 214 and 215. The operator may then manually initiate the cycle by pressing switch 216 to energize cycle relay 217. The closing of switch 216 also energizes holding circuit 218 and prepares a circuit to rim raise relay 219 through switch 220. The 35 energization of cycle relay 217 also closes switch 221 energizing rim gate relay 222. This relay energizes holding circuit 223 and closes switch 224 to actuate rim gate solenoid 225. This lowers the gate permitting the 40 ring to roll down into the orientation station. Suitable 45 manual safety stop switches 226 and 227 are employed in series with push button start switches 211 and 216. In this manner, the operator may stop the cycle or the motor 43 at any time desired.

As the ring rolls into position on the supports 22 and 50 23, it trips limit switch 228 closing the prepared circuit to rim raise relay 219. The actuation of relay 219 opens switch 229 deenergizing relay 222 to open switch 224 to deenergize ramp gate solenoid 225 to raise the ramp to preclude the next ring from rolling into the 55 orientation station. The energization of relay 219 also energizes holding circuit 230 and closes switch 231 which energizes solenoid 232 supplying air from a convenient source 233 (FIG. 22) to actuate cylinder 28 to raise the rim positioned on supports 22 and 23 of the cradle 60 21 until the ring R presses the blade 35 upwardly compressing the air within cylinder 36. At this time, limit switch 234 is closed energizing driving roll raise relay 235. The energization of relay 235 closes holding circuit 236 and closes switch 237 energizing solenoid 238. 65 Solenoid 238 supplies air to cylinder 40 raising the drive roll 41 against the bottom of the now raised ring R. The motor 43 having previously been actuated, the ring is now rotated at a relatively slow speed until the gap therein is caught by the blade 35 correctly to position such gap at the proper predetermined position.

As soon as the cylinder 36 has forced the blade 35 into the slot, the contacts 239 of the limit switch 234 are closed to deenergize relay 240 to open switch 241, deenergizing relay 235 to deenergize solenoid 238 to lower the drive roll 41 away from the ring R. As the drive

roll lowers, it trips limit switch 242 to energize relay 243. This relay actuates holding circuit 244 and closes switch 245 to energize solenoid 246. This solenoid admits air from source 232 to the blind end of cylinder 44. The transfer cylinder 44 now extends to position the rim onto the loading station when the loading station is ready to receive. The loading station signals the orientation station by tripping limit switch 247 to prepare the circuit for relay 243 to be energized by limit switch 242. Relay 243 also closes switch 248 on the loading station preparing a circuit for relay 249 subsequently described. The tripping of limit switch 247 on the loading station deenergizes relay 243 and consequently solenoid 246 to cause the cylinder 44 to retract. Retraction of cylinder 44 trips limit switch 250 energizing relay 251 to open switch 252 to deenergize relay 219 and consequently solenoid 232 of cylinder 28. This cylinder then extends to lower the cradle to receive the next ring. When the cradle is lowered and in position to receive the next ring, it trips limit switch 210 to prepare the circuit for the ramp gate solenoid 225 to actuate the ramp gate to discharge another ring. The actuation of relay 251 is delayed by time delay device 253 actuating switch 254 in series with relay 251. When the relay is energized, switch 254 is closed energizing control relay 255 which in turn opens switch 256 to deenergize relay 251 and reset the switches for the next cycle. Relays 240, 255 and 251 are control relays to set up control functions in a conventional manner and the time delay 253 delays the lift rim rise repeat cycle.

With the index table 10 positioned to receive a ring from the orientation station, switch 260 is closed preparing a circuit for relay 249. This circuit will be actuated by relay 243 of the load station when either the limit switch 261 or 262 is actuated. Switch 262 is actuated by the forge platen 125 and switch 261 is mounted on cylinder 52 of the loading station. The orientation station transfers a ring onto the load station tripping limit switch 261 energizing relay 244 in turn to energize solenoid 263 to actuate cylinder 50 moving the loading station to the extended position shown in FIG. 7. The load station is positioned at this point at the same time that cylinder 44 of the orientation station extends. The actuation of cylinder 50 trips limit switch 264 energizing relay 265 closing holding circuit 266 and through switch 267 energizing solenoid 268. Solenoid 268 actuates cylinder 52 to raise the loading station to the proper position. This in turn trips limit switch 247 to deenergize relay 243 opening switch 248. This, however, does not deenergize relay 249 to actuate cylinder 50 since the holding circuit 269 will maintain the relay energized until switch 262 is opened which is in turn controlled by the weld station forge platen 125. When such platen extends, switch 26 will be opened to cause the load station 8 to extend and raise simultaneously to position a ring on the index table. Switch 270 in series with relay 265 will be opened to deenergize solenoid 268 to lower cylinder 52 to its original position and withdraw the loading mechanism when such platen is retracted. In this manner, while the forging and welding operation is in progress, the loading station is positioning a ring on such index table.

Referring now to FIGS. 22 and 23, the cylinders 36, 28, 40 and 44 are actuated by a source of pneumatic pressure 233 through a check valve 271. The cylinder 236 is maintained under a constant pressure by maximum pressure relief valve 272. When the blade 35 is pressed upwardly to compress the air within cylinder 36, check valve 273 prohibits the transfer of pressure to supply line 274. Solenoid 232 operates a two-position directional valve 275 to control the actuation of cylinder 228. Solenoids 238 and 246 also operate respective two-position directional valves 276 and 277, each of these valves having restriction valves 278 and 279 to control the rate of exhaust from the cylinders.

The travel and lift cylinders of the loading station as shown in FIG. 23 are operated from a source of hydraulic pressure 280 which may be supplied by a dual pump system supplying fluid at a high volume and low pressure or low volume and high pressure. Hydraulic fluid at a pressure of around 400 p.s.i. will be suitable for the actuation of cylinders 50 and 52 and cylinder 52 is actuated by solenoid 268 through a two-position directional valve 281. A pressure reducing valve 282 may be employed between the supply line 283 and valve 281. In the connection to the rod end of the cylinder 52, a choke 284 may be employed with a check valve 285 in a bypass therearound. Cylinder 50 is actuated by a two-position directional valve 286 operated by solenoid 263.

The Index Table

Referring now especially to FIGS. 20 and 24, when the weld platen 125 retracts, it energizes relay 300 by closing switch 301, switch 302 having previously been closed by energization of cycle relay 217 at the orientation station. This in turn closes switch 303 to energize lock solenoid 304 to withdraw pin 114 from the aperture 115 tripping limit switch 305. This in turn energizes relay 306 closing switch 307 to energize solenoid 308 to retract the piston of cylinder 110 to index the table 10 through an arc of 90°. The traverse of the table through this arc trips limit switch 309 to energize relay 310 closing switch 311 energizing solenoid 312. This in turn admits air from a suitable source to extend cylinder 116 unlatching pawl 118. The energization of relay 312 also opens switches 313 and 314 to deenergize relays 303 and 306 respectively to deenergize solenoids 304 and 308 positioning the locking pin 114 within aperture 115 and returning the index cylinder 110 to its original position. Since the pawl 118 is unlatched, the ring gear 112 will move back to its original position without moving the table 10. The positioning of locking pin 114 within aperture 115 again actuates limit switch 305 such that the unlatched drive pawl cannot reversely be rotated through the 90° arc until the locking pin 114 is in place. The extension of cylinder 110 occurs simultaneously with the starting of the gap closing or welding operation and the loading or unloading operations. When the ring is positioned adjacent the index table 10 by the loading station, the commencement of the gap closing operation closes switch 315 energizing relay 316 to close switch 317 energizing solenoid 318. This solenoid in turn actuates clamping cylinders 100 and 101 to extend shoes 102 and 103 to lock the toggle clamping mechanism 79 and 80 correctly and firmly to position the ring with the gap properly oriented on the index table. After the ring is firmly clamped to the table, the weld platen 125 will retract opening switch 301 to retract lock cylinder 113 to repeat the cycle just described.

Referring now more particularly to FIGS. 8 and 24, it will be seen that the gauging blade 187, actuated by cylinder 109 may be operated by suitable valving mechanism 319 actuated either manually or electrically. As the lifting arms of the orientation station extend horizontally to position the rim under the clamping fixture on the indexing table, the gauging blade is lowered between the clamping mechanisms to an in-line position with the gap locating blade 35 as shown by the lower phantom line position in FIG. 8. In this lower position, the blade as well as the rim will be picked up or raised by load lift cylinder 52 to the position shown in FIG. 8. Thus the blade follows the gap from the orientation station to the table where it sets the gap for the subsequent welding operation. Upon completion of the clamping action on the index table, the gauging blade will be retracted to an "out position" until the index table 10 has been indexed 90°. At this point, the gauging blade will again be actuated to an "in position." The purpose of the gauging blade is to keep the gap oriented as the rim is slipped off the orientation cradle

onto the clamping fixtures and to set the gap required for the welding of the ring. It will be understood that the valving mechanism 319, which is illustrated as an open center, three-position directional valve, may be operated either manually or electrically, but I prefer the use of limit switches positioned around the table to actuate the valving mechanism 319 automatically to cause the gauging blade to move to its in-position at every indexing of the table 19.

The gauging blade as well as the other actuating mechanisms associated with my indexing table may be operated from a convenient source of air under pressure 320, the clamping cylinders 100 and 101 being controlled by solenoid 318 through two-position directional valve 321. A pressure reducing valve 322 may be employed in the supply line to such valve 321. The index cylinder 110 may be controlled through two-position directional valve 323, the connection from the valve to the rod end of cylinder 110 including flow control, pressure compensated valve 324 having check valve 325 in a bypass therearound. A further control valve 326 may be positioned in the rod end inlet to the cylinder 110 having check valve 327 and a restricted orifice valve 328 in bypasses therearound. The valve 326 may be cam operated by mechanisms on the table itself to act as an override or safety device for the operation of solenoid 308 to guarantee the proper position of the table prior to actuation of the cylinder 110. The lock cylinder 113 is actuated by solenoid 304 through a two-position directional valve 329. A pressure reducing valve 330 and check valve 331 are preferably positioned in the pressure inlet for valve 329. Latch cylinder 116 is controlled through cylinder 312 by two-position directional valve 332, the valves 319, 321, 323, 329 and 332 being connected to the same source of pneumatic pressure.

Referring again to FIG. 20, it will be seen that limit switches 305 and 309 also include contacts 340 and 341 respectively operating relays 342 and 343. When limit switch 305 is initially actuated, contacts 340 are opened to preclude actuation of relay 343. The same is true with contacts 341. Thus relay 342 cannot be actuated until limit switch 309 is again tripped to close contacts 341. When relay 342 is actuated, switch 344 is opened de-energizing relay 310 to prepare the circuits to relays 300 and 306 for the next cycle of operation. Relays 342 and 343 also control holding circuits 345 and 346 in a conventional manner. Relay 343 operates normally closed switch 347 in series with relay 342 so that relay 342 will not operate until both contacts 340 and 341 of the limit switches 305 and 309 have been closed. This will assure that the circuits will not be reset until the completion of the cycle. Relay 343 is connected to the weld and unload stations to start the weld and unloading operations when the table has completed its indexing movements. In this manner, it can be seen that the indexing table is controlled from the welding station through switches 301 and 315 from the orientation station by switches 302 and 348 in series with relays 300 and 316, respectively, and that the index table controls the start of the weld and unload operations through relay 343. In this manner, a progressive automatic operation of my machine components is obtained.

Unloading and Milling Stations

Referring now more particularly to FIGS. 21, 25 and 26, it will be seen that the travel cylinder 139 of the unloading mechanism shown in more detail in FIGS. 14 and 15 is actuated by a solenoid 350 controlled by switch 351 through relay 352. The closing of switch 353 by the extension of the weld platen 125 energizes such relay 352 simultaneously with the extension of the platen to move the unload clamping arm 144 toward the index table with the weld platen 125. When the unload clamping arm 144 reaches its extended position, a limit switch 354 is actuated to energize relay 355 closing switch 356 to energize solenoid 357 actuating clamping cylinders 145 and

146 to clamp the ring bead between the clamping shoes 148 and 149 respectively. Relay 355 also closes switch 358 to prepare a circuit to relay 359. When such circuit is energized, relay 359 will close switch 360 actuating solenoid 361. Solenoid 361 actuates unlocking cylinder 150. The relay 359, however, cannot be energized until both switches 362 and 363 are closed. Switch 362 is actuated by forge relay 364 and switch 363 is actuated by forge time delay relay 365. In series with the relays 364 and 365 respectively are switches 366 and 367 operated by a weld time delay relay. In this manner, the weld time delay, which may for example be three seconds, controls the energization of forge relay 364 which in turn closes a prepared circuit to time delay relay 365 to deenergize forge relay 364 after a short time interval, as for example, one second. In this manner, the relay 359 can only be actuated during the forging operation after switch 354 has been closed.

In parallel with limit switch 353, actuating travel cylinder solenoid 350 through relay 352, is a switch 368 actuated by weld platen relay 369. This relay controls the energization of a solenoid to extend and retract weld platen cylinder 132. Also in series with relay 369 is reset switch 370 and weld relay switch 371, a holding circuit 372 being employed around actuating switch 371. Relay 352 also energizes a holding circuit 373 around switches 353 and 368 to maintain such relay energized to be deenergized in a manner hereinafter described. Relay 355 also employs a holding circuit 374 for a similar purpose.

Relay 355 also closes switch 375 preparing a circuit to relay 376 which is energized when switch 377 closes upon the deenergization of relay 359. As soon as solenoid 361 has completed the unlocking operation, switch 377 closes permitting the energization of relay 376 which energizes holding circuit 378 around switch 375 and closes switch 379. Switch 379 directly energizes solenoid 380 controlling lift cylinder 152. The energization of this solenoid lowers the platform 138 until limit switch 381 is closed. The closing of this limit switch energizes relay 382 closing switch 383 to complete a holding circuit around switch 381 and switch 384. This prepares a circuit to relay 385 to be energized by the closing of travel limit switch 386. Travel limit switch 386 is actuated by the retraction of cylinder 139 upon the deenergization of solenoid 350. Relay 382 opens switch 387 deenergizing relay 352 to open switch 351. The energization of relay 385 closes holding circuit 388 and closes switch 389 to energize solenoid 390 to actuate index cylinder 161 rotating the unloading mechanism through an arc of 180° positioning the ring in front of the milling station 13. The positioning of the ring in its proper position in front of the milling station now trips limit switch 353 to re-energize relay 352 and consequently travel cylinder solenoid 350. The energization of relay 385 closes switch 391 in parallel with now open switch 387. Similarly, limit switch 353 is in parallel with switch 368 of relay 369 whereby relay 352 will be energized even though switch 368 is open. This again extends cylinder 139 to position the unload clamping arm 144 to place the ring between the upper and lower milling cutters 180 and 181. After the milling station has control of the ring, it will then signal the unloading station to reposition the components thereof in the original position in a manner hereinafter described.

The milling drive motor 395 is energized through conventional start button 396, the starting of such motor also closing switches 397 and 398 closing the main 400 to the milling circuit and closing a holding circuit around switch 396. When travel cylinder 139 of the unloading station extends, it trips limit switch 401 causing the energization of relay 402 to close switch 403 energizing solenoid 404 to raise the platform or clamping shoe 178 beneath the extended ring. Relay 402 can only be energized after the energization of relay 385 controlling

index solenoid 390 since relay 385 also closes switch 405 in series with relay 402. Relay 402 also closes holding circuit 406 in a conventional manner.

When the clamping shoe 178 is extended to the proper position beneath the ring, it trips both limit switches 407 and 408. The tripping of limit switch 407 energizes relay 409 closing switch 410 to energize solenoid 411 to extend clamping cylinder 176 firmly to press the upper clamping shoe against the inner portion of the ring firmly to clamp such ring on rockable support 173. Relay 409 also energizes holding circuit 412 in a conventional manner. The energization of relay 402 opens switch 413 in the unloading circuit simultaneously to deenergize relay 355 and solenoid 357 to retract clamping cylinders 145 and 146 to unclamp the ring as soon as it is firmly engaged by the milling station clamps.

Limit switch 408 energizes relay 414 closing holding circuit 415 and closing switch 416. This in turn energizes solenoid 417 causing mill cylinder 188 to extend raising the lower milling cutter 181 against the inside of ring R. Simultaneously relay 414 opens switch 418 again to cause deenergization of relay 352 to deenergize solenoid 350 to retract unload travel cylinder 139. The proper positioning of the lower milling cutter trips limit switch 419 energizing relay 420 closing switch 421 energizing solenoid 422 actuating rock cylinder 194 to rock the support 133 along the arcuate rails 171 and 172 the center of which is substantially the center of ring R. The energization of relay 420 simultaneously closes switch 423 and 424 to cause the unloading station to index and raise again to be positioned to unload the next following ring. Relay 420 also closes switch 425 to energize time delay relay 426, which after a predetermined time interval opens switch 427 to deenergize relay 420 and consequently solenoid 422 to permit the rock cylinder 194 to retract completing the weld bead milling operation. Relay 420 also energizes a holding circuit 428 around time delay switch 427 and relay 426 also energizes a holding circuit 429.

When the rock cylinder is retracted, limit switch 430 is closed to energize relay 431 opening switches 432 and 433. Switch 433 resets time delay relay 426 and switch 432 deenergizes relay 414 to deenergize solenoid 417 causing the lowering of mill cylinder 188. Relay 431 also energizes holding circuit 434.

When the mill cylinder 188 has lowered the cutter 181 away from the ring, limit switch 435 is closed energizing relay 436. This relay opens switch 437 to deenergize relay 402 deenergizing cylinder 404 to retract lift cylinder 166 to its original lower position. Relay 436 also energizes holding circuit 438.

Retraction of the lift cylinder 166 trips limit switch 439 to energize relay 440 to open switch 441 to deenergize relay 409, deenergizing solenoid 411 to retract clamping cylinder 176 releasing clamping shoe 179. Relay 440 simultaneously closes switch 442 energizing solenoid 443 to retract cylinder 193 and thus the entire milling cutter assembly. Relay 440 also energizes holding circuit 444.

When the cutters 180 and 181 have been withdrawn from the path of the ring R, the assembly trips limit switch 445 to energize relay 446 closing switch 447 to energize solenoid 448. Solenoid 448 controls kickoff cylinder 198 which now extends causing the kickoff arm 197 to remove the ring R from the clamping shoe 178 placing it on ramp 14 to be fed by gravity to the planishing and sizing station 15. Relay 446 also energizes holding circuit 449. When the kickoff 197 reaches its extended position, it opens limit switch 450 deenergizing relay 446 and consequently solenoid 448 causing the kickoff to return to its original position. The deenergization of relay 446 opens switch 451 to deenergize relay 440 deenergizing solenoid 443 returning the milling cutters to their original extended position. The exten-

sion of the milling cutters closes limit switch 452 energizing relay 453 opening switches 454 and 455 resetting relays 431 and 436 respectively preparing the mechanism for the next cycle of operation.

It is noted that index relay 385 of the loading station closes normally open switch 405 in series with relay 402 to provide an interlock between the index mechanism and the lift cylinder 166. In this manner, solenoid 404 can only be energized while switch 405 is closed. Normally closed switch 456 in series with recycle relay 453 is operated by relay 402 energizing lift solenoid 404. In this manner, when such solenoid is energized, it is impossible for the relay 453 to actuate the recycle switches 454 and 455. Thus, the relay 402 energizing solenoid 404 must be deenergized before such mechanism can be reset. The relays shown are provided with conventional holding circuits as illustrated insuring that they will remain energized until deenergized by the proper subsequently actuating switches to insure the proper sequence of my mechanism. The mains 400 and 457 may, if desired, be extensions of the mains 214 and 215 shown in FIG. 19.

Referring now to FIGS. 25 and 26, it will be seen that the index and unlock cylinders 161 and 158 of my unloading station are each operated by directional two-position hydraulic valves 460 and 461 controlled by solenoids 390 and 361 respectively. These cylinders are actuated by a source of hydraulic fluid under pressure 462 which may be the same as the other hydraulic components of my mechanism. Connected in the exhaust port of valve 461, I provide a variable restriction choke 463 to control the speed of operation of cylinder 161. Cylinders 145, 146, 139 and 152 are operated from a source of air under pressure 464 through check valve 465. Accumulator 466 may also be employed in the source. Each of the solenoids 357, 350 and 380 operate two-position directional valves 467, 468 and 469, respectively, to control clamping cylinders, travel and lift cylinders. In the exhaust port of the travel cylinder valve 468 are two choke valves 470 and 471 to regulate the speed of operation of travel cylinder 139.

As shown in FIG. 26, the clamp, lift and kickoff cylinders, 176, 166, and 193 are operated, respectively, through solenoids 411, 404 and 448 by two-position directional valves 472, 473 and 474. The exhaust port valve 473 has a restriction choke valve 475 positioned therein to control the speed of lift cylinder 166. These valves are actuated through a suitable source of air under pressure 476 through check valve 477. Accumulator 478 may also conventionally be employed with the above components.

A pneumatic takeup 479 employed with maximum pressure valve 480 may be used to take up the slack in drive belt 185 as the lower cutter 181 is positioned upwardly against upper cutter 180 by cylinder 188. The rock, mill and position cylinders 194, 188 and 193, are controlled through two-position directional valves 481, 482 and 483, respectively, from a suitable source of hydraulic pressure 484. The inlet to valve 482 includes a check valve 485 and a pressure reducing valve 486. The outlet from the valve to the blind end of cylinder 188 includes cam operated valve 487 having a restriction valve 488 and a check valve 489 in parallel bypassing the same. The mill cylinder 188, like the index cylinder 110, employs an external safety device such that it can only be operated after the cam has energized shutoff valve 487 insuring the proper position of the components. In the exhaust port of valve 483, I employ restriction choke valve 490 governing the speed of travel of position cylinder 193.

It will now be seen that an important part of my ring processing mechanism is my special index table which will be loaded at the same time that the cleaning station and gap closing stations are working on preceding rings and a ring is being unloaded at the fourth station to pre-

sent the ring with the gap therein closed to the subsequent milling operation. From the orientation station to the subsequent milling operation, the ring remains in its properly oriented position as the result of my special transfer and clamping mechanisms. This insures that the gap will properly be presented to the cleaning and closing stations, and such closed gap then presented to the milling station where the excess metal will be removed. By controlling the gap with the gauging blade, such excess metal can easily be kept at a minimum.

I have found that with apparatus shown in FIG. 1, I can produce as many as twenty 14-inch drop center automobile rims per minute. This means that the mechanism between ramp 5 and outlet 16 must produce approximately half that or ten rims per minute. Such high rate of production to produce accurately and economically rims of such small diameter has been accomplished only by providing the special work handling and clamping devices interlocked to operate in a manner continuously to handle a constant flow of rims.

It will now be seen that I have provided a method and apparatus for producing such drop-center wheel rims and the like at an extremely rapid rate of speed requiring relatively few pieces of apparatus and generally less floor space and fewer man hours than previously, the sequential operation of my apparatus being substantially automatic.

Other modes of applying the principle of the invention may be employed, change being made as regards the details described, provided the features stated in the following claim, or the equivalent of such, be employed.

I, therefore, particularly point out and distinctly claim as my invention:

In apparatus for forming drop-center wheel rims; means for orienting a gap in circularized stock, an index table for moving such circularized stock in oriented position

through various working operations, loading means for said index table to place such oriented stock upon the table, said loading means comprising a support, means vertically to reciprocate said support to lift such circularized stock from said orienting means to a position to be clamped upon said index table, a gap gauging blade pivotally mounted on a non-rotatable portion of said index table, and means to position said gap gauging blade in such gap of such stock while on said loading support, vertical movement of said support raising said gap gauging blade whereby said gauging blade constitutes a means to maintain such stock in oriented position and to set the gap therein when such stock is clamped to the index table.
